[57] CLAIM

The ornamental design for a combination writing instrument and bookmark, as shown and described.

DESCRIPTION

FIG. 1 is a perspective view of a combination writing instrument and bookmark showing my new design, the book depicted by means of broken lines being shown for illustrative purposes only and forming no part of the claimed design;

FIG. 2 is a perspective view in an exploded condition;

FIG. 3 is a top plan view thereof;

FIG. 4 is a bottom plan view thereof;

FIG. 5 is a side elevational view thereof;

FIG. 6 is a right end elevational view thereof;

FIG. 7 is a left end elevational view thereof;

FIG. 8 is a perspective view of a second embodiment of my new design;

FIG. 9 is a top plan view thereof;

FIG. 10 is a bottom plan view thereof;

FIG. 11 is a side elevational view thereof;

FIG. 12 is a right end elevational view thereof; and,

FIG. 13 is a left end elevational view thereof.

The portions shown in broken lines in FIG. 1 are for information only and form no part of the instant design.
